UNITED STATES PATENT OFFICE

PIERRE AUGUSTE MARCELLIN PRIOU, OF CHINON, FRANCE

MACHINE FOR AUTOMATICALLY PRINTING PHOTOGRAPHIC PROOFS

Application filed March 10, 1930, Serial No. 434,744, and in France March 11, 1929.

- It is known that photographic printing machines are usually composed of a box containing the printing lamps surmounted by a horizontal glass plate on which are placed the negatives to be copied and the masks. Usually, no device is provided for easily centering the negative plates on the masks and for subsequently holding them stationary in the chosen position. It results therefore that as the negative plates and the masks are not held, they can move during the printing operation which becomes so much the more delicate as it is also necessary to center the paper on the negative for each new impression to be effected. Once the impression is effected, difficulties are encountered and time is lost for removing the printed paper, which is in intimate contact with the negative. The present invention remedies these various inconveniences and allows:
- 1.—The adjustment of the masks according to the desired margin, and the locking in position of the same;
  - 2.—An easy and extremely rapid centering of the negative plates and vignetting-papers on the masks;
  - 3.—The absolute and instantaneous locking of these various elements relatively to each other;
  - 4.—The automatic centering of the photographic papers;
  - 5.—The automatic printing of the papers or positive plates through the medium of an exposure-counter, of any known type, mechanically controlled by the movable arm of the printing machine;
  - 6.—The automatic ejection of the printed papers whatever may be their size;
  - 7.—The automatic unlocking of the negative plates the printing of which is finished and their instantaneous replacement by other negative plates;
  - 8.—The retouching or correcting rendered extremely easy, through the intervention at the back of the glass plate of the margining plate-carrying frame, which, for that purpose, is reversible.
  - 90 By way of example, the accompanying

drawings illustrate one of the forms carrying out the invention.

Fig. 1 is a side view of the printing machine in printing position.

Fig. 2 is a corresponding front view.

Fig. 3 is a longitudinal vertical section made according to line 3—3 of Fig. 2;

Figs. 4 and 5 are partial longitudinal vertical sections explaining the operation.

Figs. 6 to 8 are partial plan views showing the mode of pivoting, on the box or cabinet of the printing machine, the various frames constituting the margining plate-carrying framing.

Figs. 9 to 11 illustrate in detail the device for unlocking the plate-carrying frame.

Figs. 12 and 13 are detail views showing a modification in elevation and plan view.

As illustrated in the drawings, the machine comprises a box 1 on one of the open side faces of which a margining plate-carrying framing can be raised and brought into printing position, as illustrated in Figs. 1 and 2; this plate-carrying framing which is pivoted at 2, at its base, on the box 1, can also be swung downward to horizontal position, as shown in Figs. 4 and 5.

The plate-carrying framing, which is held against the open inclined face of the box 1 by a counterweight 3, is constituted by three frames.

The first frame 4 supports a fixed glass-plate 5 against which bear the negatives 6. The second frame 7 carries at its middle portion another smaller movable frame or pressing frame 8 which is adapted to lock the negative in the chosen position, and to serve as an abutment for the papers 9 to be printed. For that purpose, it carries at its periphery leaf springs 11 which, bearing against small bars 12 secured on the frame 7, exert a strong pressure on the inner movable frame 8 and compel it to project on the inner face of the frame 7. This frame 7 and the frame 4 carrying the glass-plate 5, are connected at their base by hinges 13 the axis of which coincides with the pivoting axis 2 of the entire framing. Two locking bolts constituted by two spring leaves 14 each terminated by a hook 15, are secured on the upper edge of the

frame 4 and are adapted to maintain the said frame 4 and the frame 7 connected to each other, either in the raised position shown in Figs. 1 and 2, or in the bent down position 5 shown in Fig. 5. The end of the hooks 15 being cut on a bevel, the connection of the frames 4 and 7 is automatic, when a sufficient pressure is exerted on one of them. The spacing apart of these two frames 4 and 7 10 in closing position, is determined in such a manner that the pressing frame 8, pushed by the springs 11, firmly presses against the glass-plate 5, by thus locking all the negative plates 6 interposed between the said 15 frame 7 and the glass-plate 5 of the frame 4.

In order, to avoid the opening of the plate-carrying frame upon each change of negatives, an automatic unlocking device is provided. This device is composed (Figs. 9 to 20 11) of two spindles 16 journaled in supports 18 secured on the pressing frame 8. Each of these spindles carries two cams 19 bearing against metal members 20 secured on the edge of the frame 7, when an angular rotary movement is imparted in the suitable direction to both spindles 16 by the bent end 16^a, forming a crank, of these spindles. Referring to Fig. 11, it will be seen that the cams 19 are raised and do not act on the 25 frame 8; the latter, subjected to the action of the springs 11, presses the negative plates 6 against the glass-plate 5. Referring to Figs. 9 and 10, it will be seen that the cranks 16^a are raised and that the cams 19, by moving the frame 8 away from the glass-plate 5, have determined the unclamping of the negative plates 6 and their release.

The frame 7 carries on its upper side, and pivoted about a stud or spindle 21, a device 40 for locking the masks, this device being constituted by a double clip 22 provided with a spring 23 and an operating lever 24. When this lever 24 is pressed upon, the clip 22 by rocking about the stud 21 opens and allows 45 the placing in position or the removal of the masks 25. By releasing the lever 24, the spring 23 causes the clip to powerfully reclose for retaining the masks in position on the negative plates.

50 Between the frame 4 and the box 1 is arranged a vignetting-paper-carrying frame 27, which pivots about the same axis 2 as the plate-carrying framing constituted by the three frames 4, 7 and 8, and which can be 55 swung downwards at the same time as the said framing. A ground glass 28 is flush with its rear face and long spring leaves 29 are arranged on the inner side of the said ground glass and are adapted to hold in any 60 desired position the vignetting-papers 26 of all kinds which may be used. The base or support of the box 1 encloses a drawer 30 at the front of which is provided with a housing surmounted by a ground glass 32 and a 65 red glass 32^a, slidable in grooves in the di-

rection of the length of the drawer. This housing 31 contains an electric lamp 33 automatically lighting for allowing to center and to retouch or correct the negative plates 6, when the said drawer has been brought to 70 the position shown in Figs. 4 and 5, previously to the swinging downward of the plate-carrying framing. For that purpose the sides of the drawer are provided with rubbering members constituted by a resilient metal 75 blade 34 which comes in contact with a corresponding current distributing metal blade secured on the inner walls of the base of the box 1. The length of this blade is calculated in such a manner that the lamp 33 lights when the housing 31 which contains it passes under the opening of the plate-carrying framing, when the latter is folded down (Figs. 4 and 5), and that it automatically extinguishes when the drawer is completely 80 open or is in closing position.

Within the bow 1 of the machine are arranged: a red lamp 35, two carriers each supporting two white lamps 36, and sliding in parallel grooves 37, so that they can be independently moved, at will, towards the glass-plate 28 of the apparatus. The said carriers can also be removed from the grooves and can be put in any place, for the purpose of allowing to easily modify, as the operator desires, the distribution of the light on the negatives 6. For the same purpose, the white lamps 36 of each carrier can be so mounted as to pivot about the central axis which connects them to their base. Within the box 1 is also mounted a pneumatic shock absorber adapted to brake the raising movement of the plate-carrying framing, when it comes to its printing position, after ejection of the papers. This shock absorber comprises a 90 pump barrel 40, in which moves a piston 41, subjected to the action of a spring 42, which is so arranged as to bring back the piston towards the front head of the cylinder and the rod 41^a of the said piston projecting in front of the box, as illustrated in Fig. 5; this rod 41^a freely passing through an opening 37^a of the frame 27. At the opposite end, the pump barrel 40 is perforated with an air exhaust 95 orifice, the section of which can be controlled by a screw 43 terminated by a milled knob. In the example shown, this screw is provided, in the direction of its length, with a groove through which escapes the air compressed by the piston, when the latter is pushed back, against the action of its spring 42, by the plate-carrying framing at the end of the raising stroke of the latter. It will be understood that by screwing or unscrewing this screw 43 by means of its knob, it is possible 100 to control at will the speed of escape of the air; and, consequently, the resistance of the shock absorber.

On either side of the box 1, is provided an 105 opening or window 44 internally provided 110

75

80

85

125

130

with a red glass 45 sliding in horizontal slides 46. This opening or window 44 gives access to the interior of the box for modifying either the position of the lamps, or that of the vignetting-papers, etc. It also serves to give, outside the apparatus, a sufficient lighting for allowing to read the indications of the exposure-counter. This exposure counter, can, of course, be of any known construction and can be set in action by a pressure exerted by a push button, as in the exposure counters actuated by hand.

At the upper part of the box of the apparatus is mounted a double movable arm 47, pivoted at 48 on the said box, and on which is mounted, hung from springs 49, the pressing plate 50 for the paper. This double movable arm, which is balanced by a counter-weight 51, carries an operating transverse handle 52 secured at its other end and connecting both arms 47. The said double arm is also provided with a locking device holding the pressing plate 50 in its bent down position and fitted in the frame 8, when the latter is raised in printing position, as shown in Figs. 1 to 3.

This device comprises a spindle 53 which is journaled in supports secured on the double arm 47, and carries a finger 54 which hooks into the pressing frame 8 under the action of a spring 55, and which can be detached for releasing the pressing plate 50 by a pressure exerted on an operating lever 56.

On the side of the double movable arm 47 carrying the pressing plate 50, is secured a member 57, the end of which is bevelled and which carries, adjacent to its end, a roller 58. This member which accompanies the arm 57 in its displacements, is adapted:

1—To control, at the end of the folding down movement (or closing movement) of the said movable arm 47, and through the medium of the lever 59 pivoted at 60, the operation of the exposure counter, diagrammatically illustrated at 61 in Figs. 1 and 2.

2—Upon return movement (or opening movement) of the movable arm 47, to determine the ejection of the printed sheets of photographic paper, by actuation, up to a suitable point, of the plate-carrying framing, by means of the arm 57 encountering in this return movement an abutment 62 carried by the frame 4, and so arranged as to move away during the raising movement of the structure constituted by the frames 4, 7 and 8.

The exposure-counter 61 placed on the side of the apparatus, is therefore controlled by the movable arm 47 which, in its downward movement, determines, through the arm 57, the rocking of the lever 59 in the suitable direction for pressing in the push-button 63 provided in the usual manner on the exposure-counter.

In the form of construction illustrated in

Figs. 1 to 8, a vertical rod 64, which carries the push-button 63, slides in a support 65^a and is subjected to the action of a spring 67^a which pushes it upwardly.

On the upper end of this rod 64, is rigidly secured a blade 65, of small width, the end of which presses upon the upper conical end of the rod 66 for setting the exposure-counter. On the rod 64 is secured a finger 67, the end of which, passing through the rod, is held in contact, by the torsion of the spring 67^a, under an incline 68 of the support 65^a.

The operation of the apparatus described with reference to Figs. 1 to 8 and 9 to 11 is as follows:

1—*Centering and locking of the negative plates.*—By opening the drawer 30, the lamp 33 automatically lights, by the contact of the rubbing members placed on the side of the drawer and of the base. The plate-carrying framing is then rocked on to the drawer, as illustrated in Fig. 5. After opening of the hooks 15, the frame 4 carrying the glass plate 5 is raised. The counterweight 3 holds this frame 4 in the raised position shown in Fig. 4, whilst the frame 7 remains lowered. The mask 9 which it is desired to use is then placed on the said frame 7; the locking clip 22 holds this mask in position on the movable frame 8 mounted in the frame 7. The negative plate or plates 6 to be printed are then placed on the said mask, and the frame 4 carrying the glass plate 5 is swung down on to the frame 7, as shown in Fig. 5. Both frames are hooked by their upper edge by the automatic action of the hooks 15. The pressing frame 8 then directly acting on the negative plates 6 interposed between it and the glass plate 5, securely lock them in position. If it is desired to retouch or correct these negative plates the inactinic glass 33^a which covers the lighted housing 33 is moved backwardly in the grooves of the drawer 30. This displacement, shown in Figs. 4 and 5, has for effect to light the negative or negatives 6 with white light and to prevent any actinic light from reaching the sensitized papers placed in the rear compartment of the drawer 30.

The frames 7 and 4 occupying the position shown in Fig. 5, the device constituted by these frames is then raised and, being urged by the counterweight 3, is thus brought back into printing position (Figs. 1 to 3). In order to activate the operation, it is not necessary to rock and open the frame 7 carrying the pressing frame 8, at each change of negative plates. In fact the device constituted by these two frames being raised, as shown in Figs. 1 to 4, by causing the cranks 16^a rigid with the shafts 16 to rotate upwardly to the extent of a quarter of a revolution, it is possible, by the action of the cams 19 provided on these shafts, to completely eliminate

the pressure exerted by the pressing frame 8 upon the interposed negative plates; the latter can be very easily removed by one of the sides of the framing and immediately replaced by other plates. These new plates, once suitably centered, are locked in the chosen position, by the simple operation of the said cranks 16^a in the reverse direction.

2.—*Printing of the papers.*—A sheet of paper of the chosen size is placed in the pressing frame 8; the inner edges of this frame acting as an abutment, and the position of the mask 9 and of the negative 6 being adjusted once for all upon centering, it results therefrom that all the papers which may be subsequently placed in the pressing frame 8, are instantaneously and automatically margined. The movable arm 47 of the printing machine is then lowered and is automatically locked at the end of its stroke by engagement of the hook 54 with the pressing frame 8.

In this lowering movement, the member 57, secured on the side of the movable arm 47, comes in contact with the abutment 62 which, being pivoted, allows it to pass without difficulty. At the end of its stroke, the member 57 draws along, through its roller, the control lever 60 which then presses upon the push-rod 64 of the exposure-counter. This push-rod 64 by moving inwardly, draws along, by means of the blade 65, the rod 66 for setting the exposure-counter. When it has come to the end of its stroke, the finger 67, by sliding on the inclined edge 68 of the support, has sufficiently pivoted in order that the blade 65, which is rigid with the rod 64, extends beyond the setting rod 66, the top of which is thus uncovered. This rod 66 then escapes, but is braked upon starting, by the friction of its conical end against the blade 65, thus deadening the starting shock of the mechanism of the exposure-counter. This mechanism starts therefore at the precise moment the sensitized paper, placed on the negative plate, receives the pressure of the pressing plate 50. The setting in action of the exposure counter determines, in the usual manner, the lighting, then the extinguishment of the printing lamps 36. The movable arm 47 is then released by previously pressing upon the lever 56, which causes the hook 54 to rock against the action of the spring 55 and releases the said hook, from the pressing frame 8 with which it was in engagement, as shown in Figs. 1 to 3. The movable arm 47 is subsequently raised to the position shown in Figs. 4 and 5. In this return movement of the movable arm, the arm 57 first ceases to press upon the rod 64 of the exposure counter 61. This rod, pushed by the spring 67^a, immediately rises, the blade 65 coming back to its original position, above the setting rod 66.

65 The arm 57 then comes in engagement with

the finger 62 rigid with the plate-carrying framing and, consequently, draws along the latter which pivots about the shaft 2 until the said arm 57 abandons the finger 62, the plate-carrying framing then occupying an oblique position, the printed paper it contains falls down, by inertia, in the drawer 3, whatever may be its size. The plate-carrying framing urged by the counterweight 3, tends to suddenly come back to its printing position, but in this movement it comes in contact with the rod 41^a of the shock absorber, which projects in front of the box 1 and it pushes back the piston 1 which moves against the action of its spring 42, by delivering air from the cylinder 40 through the outlet orifice, the cross section of which has been regulated by the screw 43, so as to brake the return movement of the plate-carrying framing and to allow the latter to very gently come back to its place for a new impression.

In the form of construction shown in Figs. 12 and 13, the device for setting and tripping the exposure-counter 61 is constructed in the following manner:

The lever 59, which must press upon the push-button 63 of the exposure-counter, is freely mounted on a shaft 61, secured in a plate fastened in position on one of the sides of the box 1, and is subjected to the action of a spring 69 normally holding it in a raised position above the push-button 63. On the shaft 60 of this lever is loosely mounted a finger 70 which is connected to the lever 59 by a spring 71, and is held by the said spring against an adjustable abutment 72 of the said lever 59.

This finger 70 is so arranged as to be engaged by the roller 58 of the arm 57 upon raising of the pressing frame 50, and to actuate the lever 59 through the medium of the abutment 72, for pressing in the push-button 63. The free end of this finger 70 is preferably bevelled so as to prolong its contact with the roller 58 and to ensure the starting of the mechanism of the exposure-counter after closing of the pressing frame 50.

It will be understood that the extent to which the rod 64 of the exposure-counter is pressed in can be adjusted at will by screwing or unscrewing the bolt 72 constituting the abutment of the lever 59.

The spring 71, which connects the finger 70 to the lever 59, allows of rocking downwardly the said finger about the shaft 60, in order to bring it to a diametrically opposed position in which it is no longer in the path of the roller 58. In this position, the push-button 62 of the exposure-counter is lowered by hand in the usual manner.

In the form of construction illustrated in Figs. 12 and 13, the arm 57 carries a second roller 58^a, mounted on the same stud as the roller 58 and which is so arranged as to come in engagement with the lever 73 of a switch

74, for closing the circuit feeding the lamps
36, immediately upon closing of the pressing
frame 50.

Claims:—

- 5 1. An automatic printing machine for photographic proofs, comprising,—a box open on one of its side faces,—lamps adjustable in position within the said box,—a frame hinged by its lower edge on the said box, a
10 ground glass carried by this frame and adapted to serve as support for vignetting-papers and for covering the opening of the box, a latch pivoted on the box for holding the said frame in the raised position,—a plate-carrying framing comprising two frames pivoting, on their lower edge, about the axis of the ground glass frame, and adapted to be superposed and to be raised against the ground glass frame, a transparent glass for the first
15 of these frames, a frame sliding in the second one, springs arranged between these two frames for pushing back the sliding frame towards the transparent glass and resiliently pressing the negative plates previously placed on the sliding frame,—a double clip on the upper side of the second frame for holding the masks in position,—spring latches for locking together the two frames constituting the plate-carrying framing,—a counterweight for holding this framing in printing position,—two horizontal shafts carried by the sliding frame, two cams mounted on each of these shafts and adapted to bear upon the frame carrying the sliding frame for causing the latter to reenter the frame which carries it against the action of its springs and for releasing the negative plates after printing,—two arms pivoted on the upper part of the box, a pressing plate resiliently suspended between these arms, and adapted to fit in the sliding frame for pressing the photographic paper during printing,—means for locking the pressing plate in printing position,—an exposure-counter secured on the said box,—a lever pivoted on the said box for controlling the starting of the exposure-counter,—means carried by one of the arms supporting the pressing plate and adapted to actuate the said lever at the end of the folding down stroke of the pressing plate and putting in action the exposure-counter,—means carried by the plate-carrying framing and adapted to be actuated by the above mentioned means for opening this framing and unlocking the negative plates after printing.

3. An automatic printing machine for photographic proofs, comprising,—a box open on one of its side faces,—lamps adjustable in position within the said box,—a frame hinged by its lower edge on the said box, a ground glass carried by this frame and adapted to serve as support for vignetting-papers and for covering the opening of the box, a latch pivoted on the box for holding the said frame in the raised position,—a plate-carrying framing comprising two frames pivoting, on their lower edge, about the axis of the ground glass frame, and adapted to be superposed and to be raised against the ground glass frame, a transparent glass for the first of these frames, a frame sliding in the second one, springs arranged between these two frames for pushing back the sliding frame towards the transparent glass and resiliently pressing the negative plates previously placed on the sliding frame,—a double clip on the upper side of the second frame for holding the masks in position,—spring latches for locking together the two frames constituting the plate-carrying framing,—a counterweight for holding this framing in printing position,—two horizontal shafts carried by the sliding frame, two cams mounted on each of these shafts and adapted to bear upon the frame carrying the sliding frame for causing the latter to reenter the frame which carries it against the action of its springs and for releasing the negative plates after printing,—two arms pivoted on the upper part of the box, a pressing plate resiliently suspended between these arms, and adapted to fit in the sliding frame for pressing the photographic paper during printing,—means for locking the pressing plate in printing position,—an exposure-counter secured on the said box,—a lever pivoted on the said box for controlling the starting of the exposure-counter,—means carried by one of the arms supporting the pressing plate and adapted to actuate the said lever at the end of the folding down stroke of the pressing plate and putting in action the exposure-counter,—means carried by the plate-carrying framing and adapted to be actuated by the above mentioned means for opening this framing and unlocking the negative plates after printing.

2. An automatic printing machine for photographic proofs comprising,—a box open on one of its side faces,—lamps adjustable in position within the said box,—a frame hinged by its lower edge on the said box, a ground glass carried by this frame and adapted to serve as support for vignetting-papers and for covering the opening of the box, a latch pivoted on the box for holding the said frame in the raised position,—a plate-carrying frame comprising two frames pivoting, on their lower edge, about the axis of the ground glass frame, and adapted to be superposed and to be raised against the ground glass frame, a transparent glass for the first of these frames, a frame sliding in the second one, springs arranged between these two frames for pushing back the sliding frame towards the transparent glass and resiliently pressing the negative plates previously placed on the sliding frame,—a double clip on the upper side of the second frame for holding the masks in position,—spring latches for locking together the two frames constituting the plate-carrying framing,—a counterweight for holding this framing in printing position,—two horizontal shafts carried by the sliding frame, two cams mounted on each of these shafts and adapted to bear upon the frame carrying the sliding frame for causing the latter to reenter the frame which carries it against the action of its springs and for releasing the negative plates after printing,—two arms pivoted on the upper part of the box, a pressing plate resiliently suspended between these arms, and adapted to fit in the sliding frame for pressing the photographic paper during printing,—means for locking the pressing plate in printing position,—an exposure-counter secured on the said box,—a lever pivoted on the said box for controlling the starting of the exposure-counter,—means carried by one of the arms supporting the pressing plate and adapted to actuate the said lever at the end of the folding down stroke of the pressing plate and putting in action the exposure-counter,—means carried by the plate-carrying framing and adapted to be actuated by the above mentioned means for opening this framing and unlocking the negative plates after printing.

- this framing in printing position,—two horizontal shafts carried by the sliding frame, two cams mounted on each of these shafts and adapted to bear upon the frame carrying the sliding frame for causing the latter to reenter the frame which carries it against the action of its springs and for releasing the negative plates after printing,—two arms pivoted on the upper part of the box, a pressing plate resiliently suspended between these arms, and adapted to fit in the sliding frame for pressing the photographic paper during printing,—a hook pivoted on the arms carrying the pressing plate and adapted to enter a staple of the frame carrying the sliding plate for locking the pressing plate in the printing position,—an exposure-counter secured on the said box,—a lever pivoted on the said box for controlling the starting of the exposure-counter,—an arm rigid with members supporting the pressing plate, a roller carried by this arm and adapted to come in contact with the said lever and to put in action the exposure-counter at the end of the folding down stroke of the pressing plate,—means carried by the plate-carrying framing and adapted to be actuated by the above mentioned means for opening this framing and unlocking the negative plates after printing. 70
- 15 5. An automatic printing machine for photographic proofs, comprising,—a box open on one of its side faces,—lamps adjustable in position within the said box,—a frame hinged by its lower edge on the said box, a ground glass carried by this frame and adapted to serve as support for vignetting-papers and for covering the opening of the box, a latch pivoted on the box for holding the said frame in the raised position,—a plate-carrying framing comprising 75 two frames pivoting, on their lower edge, about the axis of the ground glass frame, and adapted to be superposed and to be raised against the ground glass frame, a transparent glass for the first of these frames, a frame sliding in the second one, springs arranged between these two frames for pushing back the sliding frame towards the transparent glass and resiliently pressing the negative plates previously placed on the sliding frame,—a double clip on the upper side of the second frame for holding the masks in position,—spring latches for locking together the two frames constituting the plate-carrying framing,—a counterweight for holding this framing in printing position,—two horizontal shafts carried by the sliding frame, two cams mounted on each of these shafts and adapted to bear upon the frame carrying the sliding frame for causing the latter to re-enter the frame which carries it against the action of its springs and for releasing the negative plates after printing,—two arms pivoted on the upper part of the box, a pressing plate resiliently suspended between these arms, and adapted to fit in the sliding frame for pressing the photographic paper during printing,—a hook pivoted on the arms carrying the pressing plate and adapted to enter a staple of the frame carrying the sliding plate for locking the pressing plate in the printing position,—an exposure-counter secured on the said box,—a lever pivoted on the said box for controlling the starting of the exposure-counter,—an arm rigid with members sup- 80

porting the pressing plate, a roller carried by this arm and adapted to come in contact with the said lever and to put in action the exposure-counter at the end of the folding down stroke of the pressing plate,—an abutment pivoted on the plate-carrying framing and adapted to be engaged by the roller of the arm rigid with the support of the pressing plate and to rock the said framing in the direction for opening, in order to unlock the negative plates at the end of the printing operation and during the return movement of the pressing plate.

6. A printing machine as claimed in claim 1 in which the arm rigid with the means supporting the pressing plate controls, during its lowering movement, the starting of the exposure-counter and the closing of the electric circuit feeding the lamps of the printing machine.

The foregoing specification of my "machine for automatically printing photographic proofs" signed by me this 21 day of February, 1930.
